PROPELLION WHEEL

Rainer H. Knipping, San Antonio, Tex.

Application February 24, 1948, Serial No. 10,231

2 Claims. (Cl. 170—142)

1

The invention relates to a propeller wheel and in particular to an improved paddle wheel construction for propelling vessels.

In the power wheel construction heretofore used, one of the primary objects is that the type wheel employed causes considerable vibration due to the straight type of blade or bucket employed. Additionally, the disk type wheel is highly inefficient and very little of the power transmitted thereto is used in propelling the vessel.

An object of the present invention, therefore, is to overcome the above mentioned difficulties.

Another object of the invention is to provide a propulsion wheel which has a plurality of propulsion elements thereon arranged to enter the water without undue shock being transmitted to the propulsion wheel.

Another object of the invention is to provide in a propulsion wheel, the propulsion of elements which are designed to more or less trap the water within such elements, so that the resistance of the water to the movement of the propulsion elements therethrough is increased, whereby a more efficient wheel is attained.

Another object of the invention is to provide a discharge port in each of a plurality of propulsion elements arranged on a propulsion wheel so that water trapped therein during the power stroke of such elements can be released as the elements leave the water.

A further object of the invention is to provide a propulsion wheel which is highly efficient and which can be used to propel the vessel in either a forward or backward direction.

It is a still further object of this invention to provide a propulsion wheel having a plurality of propulsion elements arranged to enter the water with minimum resistance but also arranged to offer a maximum resistance to the movement of water as the propulsion elements move therethrough.

A still further object of the invention is to provide a propulsion wheel which is sturdy in construction and well braced so as to attain a high efficiency on one hand, while withstanding the rigorous treatment usually attendant with the use of such wheel.

Other and further objects and advantages will become more readily apparent from a consideration of the following description and drawing wherein:

Fig. 1 is an end view of a construction in accordance with the invention taken on the line 1—1 of Fig. 2;

Fig. 2 is an elevational view showing the ar-

2

angement of the propulsion elements upon the wheel or drum;

Fig. 3 is a perspective view more clearly illustrating the arrangement of the propulsion unit; and

Fig. 4 is an enlarged detail of the flow port formed at the convergence of two adjacent plates in one of the rows of the propulsion elements.

In Fig. 1 a propulsion wheel is illustrated at 2 and is shown as comprising a cylindrical drum 3 which has the axle 4 secured thereto. The drum 3 may or may not have its ends 5 closed and such ends are preferably closed so that the drum will be buoyant when immersed in the water and water will not ride on the inner periphery as in the case where the wheel is open at the ends to allow water to pass therethrough. A plurality of rows 19 of plates 9 combine with the drum periphery 7 in forming the propulsion unit 6. These plates 9 upstand outwardly from the periphery 7 a suitable distance, depending upon the size of the vessel and the exact specification or performance desired from the propulsion wheel 2.

The propulsion wheel is arranged to be secured to a vessel at either the stern or in the center or on the side. Any suitable power transmission means can be connected to the axle 4 to impart rotation to the wheel.

The plates 9 of each row 19 are axially aligned on the drum and alternate plates are slanted at oppositely extending, substantially equal angles with respect to a transverse plane through the drum axis. The propulsion elements or buckets which are formed by the plates 9 are secured to the drum by any suitable means, such as a weld or the like.

The plates 9 are arranged on the drum so that two adjacent plates form in cross-section two of the sides of substantially an equilateral triangle, the base side being represented by the dotted line 10. Each two adjacent plates 9 of a row 6 combine in comprising a bucket 8, and the diverging ends of these two adjacent plates 9 have therebetween the opening 11, while the converging ends 16 provide the substantially smaller opening or flow port 12 through which water may be discharged as the drum portion containing this row 9 rotates out of the water.

As more clearly shown in Fig. 4, the flow or escape port 12 is formed by the flanges 13 on the ends of the plates 9. Such flanges are spaced a short distance apart to provide the flow passage 12 which extends for substantially the length

of the radially extending edges 14 of the plates 9. Any suitable means, such as the strap 15, can extend between the adjacent flanges 13, and be secured thereto, in order to brace and rigidify the propulsion wheel.

By arranging the plates 9, as hereinabove described, to form the propulsion element 6, the wheel can be used to propel the vessel in either a forward or rearward direction, since a plurality of three-sided buckets 8 are provided. As shown most clearly in Fig. 2, the plate surfaces 20 and 20' of two adjacent plates 9 combine with the drum periphery 7 to define one such three-sided bucket, while the surface 21 opposite the surface 20' and the surface 22 of the next successive plate 9 combine with the drum periphery to define an adjacent three-sided bucket 8. It follows as a result of this construction that the adjacent ports 12 in any row are provided to discharge in opposite directions.

As the wheel is rotated, the rows 19 of buckets 8 successively enter the water with a minimum of resistance and so as to entrap water within the bucket while creating a minimum of vibration in the propulsion wheel 2. Since the ports 12 are much smaller in cross sectional area than the openings 11 between the diverging ends of two adjacent plates 9, the water will be more or less constricted between the plates 9. This increases the resistance of the water to the movement of the plates therethrough, so that in effect, the wheel thrusts the vessel in the direction that it is moving.

The water will remain constricted or trapped between the plates 9 for a greater portion of the arc of travel through the water. As the buckets continue to move upwardly and out of the water, the trapped water within the buckets will fall outwardly and will also be discharged through the flow ports 12.

Water drag on the paddle is, therefore, eliminated and energy heretofore used in lifting the water on the side where the rows 19 emerge, can now be diverted to a useful form of work.

The construction and arrangement of the plates 9 to form the rows 19 included in the propulsion element 6 is such that the flow of water therebetween is directed and controlled and it is to be additionally noted that a far greater surface area is presented to the water as the rows 19 travel successively therethrough. In this manner, it is possible to have a smaller wheel while at the same time doing a proportionate larger amount of work.

The construction of the plates and their arrangement on the wheel is such that they are all braced together and the whole affords a sturdy construction which is well adapted for the work for which it is intended.

It seems obvious that the size of the buckets formed by the plates 9 in combination with the drum periphery 7 and the size of the passages 12, can be varied to meet the requirement of capacity, load, and other such factors, in the design of the wheel.

Broadly the invention contemplates a propulsion wheel and in particular, an improved propulsion wheel, which has a plurality of rows of buckets arranged in a propulsion unit so that a minimum of resistance is offered as the rows of buckets enter the water, but a maximum

amount of resistance is created between the buckets and the water in order to obtain useful work from the buckets to propel the vessel.

What is claimed is:

1. A propulsion wheel including, a drum having closed ends, an axle extending from said ends, a plurality of rows of buckets on said drum and extending axially thereof, each of said rows of buckets including a plurality of plates upstanding from the periphery of the drum with the alternate plates in each row slanted at oppositely extending, substantially equal angles from a plane transverse to the drum axis so that two adjacent plates comprise a bucket and in cross-section form two sides of a triangle, the converging ends of said plates being separated to provide a small opening therebetween, the base of the triangle being completed by the distance across the opening between the diverging edges, the rotation of the drum entrapping water in the buckets of each row as that row enters the water, and the small openings providing escape ports for the water trapped within the buckets as further rotation moves that portion of the drum out of the water.

2. A propulsion wheel including, a drum having closed ends, an axle extending from said ends, a plurality of rows of buckets on said drum and extending axially thereof, each of said rows of buckets including a plurality of plates upstanding from the periphery of the drum with the alternate plates in each row slanted at oppositely extending, substantially equal angles from a plane transverse to the drum axis so that two adjacent plates comprise a bucket and in cross-section form two sides of a triangle, the converging ends of said plates being separated to provide a small opening therebetween, the base of the triangle being completed by the distance across the opening between the diverging edges, the rotation of the drum entrapping water in the buckets of each row as that row enters the water, and the small openings providing escape ports for the water trapped within the buckets as further rotation moves that portion of the drum out of the water, the terminal portions of the converging ends being flanged and tied together outwardly by an axially extending strap member.
